UNITED STATES PATENT OFFICE.

WILLIAM C. PRICE, OF BEATTYVILLE, KENTUCKY.

PICK-POLE.

1,186,831.

Specification of Letters Patent. Patented June 13, 1916.

Application filed March 23, 1916. Serial No. 86,243.

To all whom it may concern:

Be it known that I, WILLIAM C. PRICE, a citizen of the United States, residing at Beattyville, in the county of Lee and State of Kentucky, have invented a new and useful Pick-Pole, of which the following is a specification.

This invention relates to logging implements of the type known as "pick poles", such as are used in directing logs into a boom pocket as they pass along the sheer. The poles heretofore used for this purpose have been provided with pointed stems rigid with the pole and the stems and poles have often become broken because of the sudden and unavoidable strains to which they have been subjected, such breakage resulting in the loss of the logs engaged by the stems.

One of the objects of the present invention is to provide a structure of this character utilizing a stem or point which is shiftable relative to the pole so that should the implement be subjected to a strain such as would ordinarily break a pole of the type commonly used, the relative movement of the stem and pole would be such that injury to the parts would not result.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—Figure 1 is a plan view of a pole embodying the present improvements, the stem being shown in engagement with the log. Fig. 2 is a view partly in section and partly in elevation of a portion of the pole and showing its connection with the stem, certain of the positions to which the pole may move relative to the stem being indicated by dotted lines. Fig. 3 is a section on line A—B Fig. 2.

Referring to the figures by characters of reference 1 designates a pole of any desired proportions one end of which is fitted with a ferrule 2 which projects beyond the end of the pole and terminates in a socket 3 hav-

ing opposed portions somewhat flattened, as indicated at 4. The socket is elongated in the direction of the length of the ferrule and constitutes a seat for a head 5 from which extends a tapered stem 6 pointed as shown. An ear 7 extends from the innermost portion of the head and is engaged by one end of a coiled spring 8 housed within the ferrule 2, the other end of the coiled spring being attached to an eye 9 provided at one end of a rod 10. This rod is extended within a portion of the pole and has one end extended outwardly to the side of the pole as shown at 11.

Under normal conditions the spring 8 holds the head 5 drawn inwardly against the innermost portion of the socket 3 and maintains the longitudinal axes of the stem and pole in alinement. Thus when the point of the stem is driven into a log a portion of which has been indicated at L the thrust will be directed from the wall of the socket 3 against the head 5 and thus to the point. Should the pole be subjected to a lateral strain, as for example by the impact of another log against the side of the pole, the pole would be free to swing relative to the point, as indicated by dotted lines in Fig. 2, thus avoiding all danger of a break. During the operation of driving the point into a log, the wall of the opening in the outer end of the socket 3 fits close to and surrounds the thick end portion of the stem, thus holding the stem against swinging movement. However, when the pole is pulled away from the point, the wall of said opening in the socket is brought to position opposite an annular groove or channel formed in the inner end portion of the point so that the point can thus swing relative to the ferrule. Spring 8, as before pointed out, holds the point normally drawn back into the ferrule and, should the point be swung out of its normal position, this spring will always return it back to such position after the point has been released from a log.

What is claimed is:—

1. A device of the class described including a pole, a pointed stem mounted to swing and slide relative thereto, and yielding means for holding the stem normally against swinging and sliding movements.

2. A device of the class described including a pole having a socket, a pointed stem, a head at one end of the stem, yielding means for holding the head normally pressed

against the inner portion of the socket, said socket and stem coöperating to hold the stem against pivotal movement when retracted against the seat.

- 5 3. The combination with a pole having a socket at one end, a head within the socket, and a pointed stem projecting from the head, said head and stem being slidable relative to the socket and said stem being capable of 10 swinging relative to the socket when in outwardly projected position, of yielding means for holding the head normally seated against the inner portion of the socket and the stem normally out of projected position.
- 15 4. The combination with a pole and a socket member at one end of the pole provided with an opening, of a head slidably mounted within the socket member, a pointed stem projecting from the head and 20 through the opening, the wall of the opening coöperating with the stem for holding the stem against swinging movement when the head is in normal position, yielding means engaging the head for holding it in 25 normal position, said stem having an annular depression for the reception of the wall of the socket opening when the stem is swung relative to the socket member and while in projected position.
- 30 5. The combination with a pole, an elongated socket at one end thereof, of a head slidably mounted in the socket, a pointed stem projecting from the head and beyond the socket, the wall of the socket coöperating 35 with the stem for holding the stem against pivotal movement when in its normal position, yielding means for holding the stem normally retracted to one limit of its

sliding movement, said stem having a reduced portion adapted, when the stem is moved outwardly from its normal position, to coöperate with the wall of the socket to permit the pivotal movement of the stem relative to the socket.

6. The combination with a pole, a ferrule 45 on one end thereof and having an elongated socket, and a spring housed within the ferrule, of a head slidably and pivotally mounted within the socket and normally held retracted by the spring, a pointed stem 50 projecting from the head and beyond the socket, the walls of the socket coöperating with the stem to hold the stem against pivotal movement when the head is retracted.

7. The combination with a pole, a ferrule 55 extending from one end thereof and an elongated socket at the end of the ferrule and having an opening, of a head slidably mounted in the socket, a pointed stem projecting from said head and through the 60 opening, said stem being cut away to permit swinging movement of the stem relative to the socket when the stem is projected outwardly relative to the socket, and a spring housed within the ferrule and connected to 65 the head for holding said head normally retracted, the wall of the socket coöperating with the stem to hold said stem against pivotal movement when retracted.

In testimony that I claim the foregoing 70 as my own, I have hereto affixed my signature in the presence of two witnesses.

WILLIAM C. PRICE.
